UNITED STATES PATENT OFFICE.

WILLIAM E. BAKER, OF ERIE, PENNSYLVANIA.

FLUID-PRESSURE ENGINE.

Application filed April 9, 1921. Serial No. 460,034.

To all whom it may concern:

Be it known that I, WILLIAM E. BAKER, a citizen of the United States, residing at Erie, in the county of Erie and State of Pennsylvania, have invented certain new and useful Improvements in Fluid-Pressure Engines, of which the following is a specification.

My invention relates to fluid pressure engines, particularly those of the rotary type and comprises an improved construction and mounting of the fluid pressure distributing valve.

One object of my invention is to increase the efficiency of an engine of this type by mounting the distributing valve on the engine casing thereby avoiding pressure by one side of the valve body against its bushing due to the presence of fluid under pressure between the opposite side of the body and the adjacent portion of its bushing.

Engines of this type are usually steam driven and another object of my invention is to isolate the live steam in the valve body inlet chamber from the exhaust steam in the exhaust passage thereby maintaining the temperature of the live steam.

An additional object of my invention is to prevent the expansion of the valve body, due to high temperature and steam pressure, from retarding the operation of the valve and engine. I prefer to do this by constructing the valve in two parts, utilizing a split ring between the valve body and the valve bushing, and a further object of my invention is to provide a novel device for contracting this ring automatically when the interior pressure tends to bind the ring and bushing.

An additional object of my invention is to reduce the area or volume of the inlet chamber of the valve and to locate the cut off plate within the reduced chamber.

Other objects of my invention are to provide particular features of construction as hereafter described, to enable the valve mechanism to perform its functions efficiently.

The accompanying drawings illustrate a selected embodiment of my invention incorporated in a rotary engine, but I do not limit myself to this particular embodiment of installation as will more fully appear hereinafter.

Fig. 1 is a vertical transverse section

through the distributing valve and associated parts and the casing which contains same, and on the line 1—1 of Fig. 2.

Fig. 2 is a section taken on line 2—2 of Fig. 1.

Fig. 3 is a section similar to that shown in Fig. 1, but illustrating a modification of my invention.

Fig. 4 is a section on line 4—4 of Fig. 3.

Fig. 5 is a side elevation, partly in section showing my improved distributing valve embodied in a rotary engine.

Fig. 6 is a perspective view of the valve body ring.

Fig. 7 is a plan view of the valve body 3 and valve body ring 4 at the split in said ring.

Fig. 8 is a perspective view of the valve body, partly in section.

Referring at first to Figures 1, 2, 6, 7 and 8 of the drawings, which show the preferred embodiment of the valve, it will be explained that the reference character 1 designates a cylindrical casing which is carried by and rotates with the rotatable crank 80 case of the engine as will hereinafter appear. The valve casing is provided with a plurality of ports 11 leading to the respective cylinders of the rotary engine. Within the valve casing is a valve unit which is normally stationary and is made up of the two elements 3 and 4. The element 3 is the valve body, which is segmental in general form and includes a cylindrical hub 5, through which steam or other fluid pressure is led to the valve, radial arms 9 and a rim 10 carried by the outer ends of said arms. The arms 9 are hollow and constitute fluid pressure passages leading from the hub 5 to the rim 10 so as to conduct pressure from the interior of the hub to the respective recesses 10' in the outer periphery of the rim 10, which recesses constitute ports for successive alignment with the ports 11 of the casing 1. The outer face of the rim 10 is provided with a boss or raised portion 10^a, and the ports 10' are formed in this boss or raised portion.

Inasmuch as the valve body is segmental in shape I employ the packing ring 4 embracing the valve member 3 and completing a circular valve unit so as to give the valve a working fit within the cylindrical casing and also prevent the escape of fluid pressure. If desired a bushing 2 may be em- 110

ployed between the valve unit and the casing 1, said bushing being held to the casing 1 so as to rotate therewith and of course provided with ports registered with 5 the ports 11 of the casing.

As best shown in Figures 6 and 7 of the drawings, it will be seen that the packing ring 4 is a split ring, the transverse split being shown at 12. In one side of the 10 packing ring 4 there is a peripheral slot 19 in which snugly fits the boss 10^a of the valve body 3, whereby the two members are united for simultaneous rotation in reversing the engine. Diametrically opposite the 15 slot 19 a peripheral groove or channel 20 is formed in the exterior of the packing ring 4, and this groove or channel is designed for the relief of back pressure from the engine cylinders as will be hereinafter 20 explained. Between the channeled portion 20 of the packing ring 4 and the hub 5 of the valve member there is a space 21, and in this space is received any steam that may 25 escape from the ports 10' and between the rim 10 of the valve and the packing ring 4. The pressure in the space or chamber 21 will tend to expand the split packing ring 4 and create undesirable friction 30 against the valve casing, and to overcome this objection, means is provided, within the chamber 21 and actuated by the pressure therein to contract the packing ring and thus off-set the tendency of the pressure 35 to expand the ring. In accomplishing this object, a substantially radial cylinder 18 is provided upon the inner periphery of the packing ring 4 and within the chamber 21. Within the cylinder 18 there is a piston 17 open to pressure in the 40 chamber 21 through the open inner end of the cylinder 18. Associated with the piston 17 is a bell crank lever 14 fulcrumed at 15 in a seat or recess provided in one end of the valve body 3. The short arm 14^a of 45 the bell crank lever engages against one side of a boss or shoulder 16 on one end portion of the packing ring 4, the opposite end of the packing ring being secured to the valve body by a suitable fastening such as shown 50 at 13 in Figures 1 and 7. With this construction, pressure which accumulates in the chamber 21 tends to move the piston 17 to the right, thereby rocking the bell crank 14 on its fulcrum 15 so that its short arm 14' 55 presses against the abutment 16 and draws the free end of the split packing ring 4 towards the opposite and fixed end and thus contracts the packing ring and prevents a too tight fit of the packing ring 60 against the valve casing as would otherwise occur under pressure accumulating in the chamber 21.

For the purpose of controlling the flow 65 of fluid pressure from the valve hub 5 into the radial distributing passages 9, there is

provided a cut-off 8 in the form of a segmental plate fitting within the hub and connected by an arm 8' to a rotatable rod 7, so that by rotating the rod 7, the cut-off 8 may be set within the hub 5 to leave the 70 passages 9 open, as in Figure 1 or to close any one or more of the inner open ends of the distributing passages 9, whereby the engine may be started and stopped and the supply of fluid pressure controlled. 75

By reference to Figure 2 it will be seen that the cylindrical valve casing 1 has opposite side walls 1^a and 1^b provided respectively with central cylindrical chambers 1^c and 1^e. The chamber 1^c is closed at its 80 outer end, but the end wall of the chamber 1^e is provided with an outwardly directed sleeve portion 1^f through which extends one end portion of the valve hub 5. The inner end portion of the hub 5, which carries the 85 segmental valve member 3 is slightly enlarged and occupies the chambers 1^c and 1^e. Suitable anti-friction bearings 6 are employed in the chambers 1^c and 1^e and between the hub 5 and the cylindrical portions 90 of said chambers, whereby the casing 1 is mounted to rotate upon the stationary hub 5. These anti-friction bearings maintain the centered relation of the valve casing 1 and the valve body regardless of the steam 95 pressure within the casing, which steam pressure has a tendency to force the valve 100 3 edgewise and against the interior walls of the casing 1, as will be understood by reference to Figure 1 of the drawings, because of the steam pressure acting through the distributing passages 9 and against the interior of the cylindrical portion 1 of the valve casing. 105

For an understanding of the application and operation of the present distributing valve, reference is made to Figure 5 of the drawings wherein 36 designates a stationary engine casing within which is rotatably mounted the valve of the present invention 110 carried by and rotatable with the crank case of a rotary engine. The crank case includes opposite side plates 38 and 39 between which are carried a series of engine cylinders, one of which has been shown at 33, 115 and includes a piston 31. Exhaust ports are shown at 32 in opposite sides of the cylinder. Suitably connected to the piston is a connecting rod 40 provided with an eccentric strap 41 embracing one of a series 120 of fixed eccentrics 42 which are secured to a fixed head 43, as by suitable fastening means 44. The head 43 is carried by a sleeve 45 extending through an opening in the stationary casing 36 and held therein 125 against rotation by a key 46. Four fixed eccentrics 42 have been shown, one for each engine cylinder. The crank case side plate 38 is mounted to rotate on the fixed sleeve 45, and a suitable anti-friction bearing 47 is 130

provided between the plate 38 and the sleeve 45. The opposite crank case face plate 39 is carried by the adjacent side wall ^{1^a of the valve casing, and is shown in the drawing as integral therewith, although it may be bolted or otherwise secured thereto. A power shaft 48 is rotatably mounted in the sleeve 45, extends through the fixed eccentricities 42 and has its inner end secured to the crank case side plate 39 by suitable fastenings, one of which has been shown at 49, whereby the shaft will rotate with the crank case.}

The valve of the present invention is located between the rotary crank case and the left side of the stationary engine casing 36, and each valve port 11, is connected with the outer end of one of the engine cylinders 33 by a pipe or conduit 11^a. The sleeve 1^c and the valve hub 5 extend outwardly through the left side of the stationary engine casing and through a stuffing box 50 carried by the casing. An anti-friction bearing 51 is provided between the sleeve 1^c and the stationary casing 36, which together with the bearing 47 maintains the rotary crank case concentric upon the axial support afforded by the fixed sleeve 45 and the fixed hub 5 of the valve. Carried by the outer end of the sleeve 1^c is a stuffing box 52 surrounding the hub 5 which latter projects beyond the stuffing box and connects with an elbow 53 that is in communication with a source of fluid pressure. The pressure supply pipe, not shown, which connects with the elbow of course holds the latter in place, and the hub 5 is mounted for adjustable rotation in the elbow. Between the elbow and the stuffing box 52, there is a lever 54 which is clamped upon or otherwise secured to the hub 5, for convenience in adjustably rotating the same to bring the distributing passages 9 of the valve to either of two diametrically opposite positions so as to effect reversing of the engine. The rod 7 extends through a stuffing box 55 on the elbow 53, and on its outer end is provided a lever 56 for convenience in rotating the rod 7 which in turn rotates the cut-off member 8 to open and close the inner ends of the distributing passages 9 for throttling the steam supply. The inner end of the hub 5 is closed in any suitable manner as by a plug 57, to prevent the escape of steam around the inner end of the hub and into the bearings 6.

In the operation of an engine as illustrated in Figure 5 and embodying the valve of the present invention, it will be explained that fluid pressure, such as steam on being admitted to the elbow 53, flows through the hub 5, then through the distributing passages 9 of the valve, see Figure 1, to the valve ports 10 and thence through the valve casing ports 11 and the respective conduits

11^a to the outer ends of the respective engine cylinders 33, whereby the pistons of the respective cylinders will be successively forced inward, and by reason of the action of the connecting rod 40 and the eccentric strap 41 on the coacting fixed cam or eccentric 42, the crank case will be caused to rotate around its axial support constituted by the parts 5 and 45. As the power shaft 48 is connected to the crank case, said shaft 75 will be driven by and rotate with the crank case. It will now be understood that the valve casing made up of the parts 1, 1^a and 1^b, best shown in Figure 2 of the drawings, rotates with the crank case and therefore 80 turns around the fixed or stationary valve member 3, whereby steam is supplied to the respective engine cylinders as the ports 11 come into registration with the successive ports 10 of the stationary valve member. 85 Exhaust from each cylinder 33 takes place through the exhaust ports 32, in the usual manner and into the stationary engine casing 36 from which it escapes through the exhaust pipe 37. On the return stroke of 90 the piston 31, and after the latter closes the exhaust ports 32, the back pressure created in the cylinder will be conducted back through the conduit 11^a, the port 11 and into the exhaust channel or conduit 20 of the 95 packing ring portion 4 of the valve, and thence through one or more of the ports 11 to such engine cylinders as have their ports 32 uncovered, whereby such back pressure will escape through the exhaust ports 32 into 100 the engine casing 36 and thence through the exhaust pipe 37. It will now be understood that by having the exhaust channel 20 diametrically opposite and therefore remote from the distributing passages 9 of 105 the valve, and also separated therefrom by the space 21, that the relatively cool exhaust steam which is being conducted off through the channel 20 is remote from the incoming hot live steam, and therefore the 110 back pressure exhaust is maintained so far away from the incoming live hot steam that the latter is not cooled by the back pressure exhaust.

While I have illustrated in Figure 5 one 115 form of means for effecting rotation of a plurality of radially disposed engine cylinders, it will of course be understood that means other than fixed cams or eccentricities and eccentric straps may be employed for 120 accomplishing this purpose, as the present valve invention is in nowise dependent upon any form of means for effecting rotation of the crank casing.

In Figures 3 and 4 I have illustrated a 125 slight modification in the valve 3, and instead of having the segmental valve member and the packing ring 4 of Figure 1, the valve member is circular so as to have a working fit within the valve casing, and the back pres- 130

sure exhaust channel 20^a is provided in the periphery of the valve member 3 diametrically opposite the distributing passages 9, so that it will be understood that the relation of the live steam distributing passages 9 and the back pressure exhaust channel is the same in each form of the valve. In the form shown in Figure 3, the valve 3 is of skeleton formation so as to provide the space or spaces 22 having the function of spacing the channel 20^a from the distributing passages 9 the same as in Figure 1. However, steam cannot get into the spaces 22, except by leakage through the pores of the metal, and such leakage is negligible. In this embodiment of the valve, cylindrical flanges 24 are provided upon the opposite side walls of the valve casing and are received within circular grooves 25 formed in the valve body and assist in preventing the escape of steam into the spaces 22 of the valve body.

The prime difference between the valve constructions shown in Figures 1 and 3 is that in Figure 3 the valve is an integral casting, whereas in Figure 1 the valve unit is made up of a segmental valve body 3 and the split ring 4 thereby to compensate for any expansion of the valve body due to high temperature and steam pressure through the contraction of the split ring 4 in the manner hereinbefore described.

I claim:

1. In a valve for a fluid pressure engine, a rotatable casing, a valve bushing, a stationary valve body ring rotatably settable within said bushing, a valve body within said ring and rotatably settable therewith, and fluid pressure distributing passages in said body projecting through said ring into contact with said bushing.

2. In a valve for a fluid pressure engine, a rotatable casing, a valve bushing, ports in said bushing and casing, a stationary valve body ring rotatably settable within said bushing, a valve positioned within said ring and rotatably settable therewith, a distributing sector in said body projecting through said ring, a fluid pressure inlet in said body, and ports in said sector adapted to align with said bushing and casing ports.

3. In a valve for a fluid pressure engine, a rotatable casing, a valve bushing, a stationary valve body ring rotatably settable within said bushing, a peripheral slot in said ring, a valve body rotatably settable with said ring and comprising a fluid pressure distributing sector projecting radially through said slot, a fluid pressure inlet axially disposed in said body, and supply ports radially disposed in said sector.

4. In a valve for a fluid pressure engine, a rotatable casing, a valve bushing, ports in said bushing, a stationary valve body ring rotatably settable within said bushing, a back pressure exhaust passage in said ring

adapted to be connected with one or more of said ports, a valve body within said ring rotatably settable therewith and projecting, in part through same, and provided with a fluid pressure inlet and with supply ports adapted to be connected with said bushing ports. 70

5. In a valve for a fluid pressure engine, a rotatable casing, a valve bushing, a stationary valve body ring rotatably settable within said bushing, a peripheral slot in said ring, a valve body rotatably settable with said ring and comprising a fluid pressure distributing sector projecting radially through said slot, a fluid pressure inlet in said body, supply ports radially disposed in said sector and means for preventing the fluid pressure between said bushing and said sector from forcing said body against said ring on the side opposite said sector. 85

6. In a valve for a fluid pressure engine, a rotatable casing, a valve bushing, a stationary valve body ring rotatably settable within said bushing, a peripheral slot in said ring, a valve body rotatably settable with said ring and comprising a fluid pressure distributing sector projecting radially through said slot, a fluid pressure inlet in said body, supply ports radially disposed in said sector and a floating mounting for said valve body in said casing whereby the fluid pressure between said bushing and said sector is prevented from forcing said body against said ring on the side opposite said sector. 95

7. In a valve for a fluid pressure engine, a rotatable casing, a stationary valve for distributing fluid under pressure through said casing comprising a valve body ring and a valve body and journaling means for said ring on said casing. 100

8. In a valve for a fluid pressure engine, a casing, a stationary valve for distributing fluid under pressure through said casing comprising a valve body ring and a valve body, and anti-friction bearings between the casing and the valve body. 110

9. In a valve for a fluid pressure engine, a rotatable casing, a circular valve bushing contained therein, a stationary circular distributing valve body within said bushing and means for mounting said body on said casing independently of said bushing. 115

10. In a valve for a fluid pressure engine, a distributing valve having inlet and supply passages located on one side of an axial plane, a back pressure exhaust passage located on the opposite side of said plane and spaced from said inlet and supply passages. 120

11. In a valve for a fluid pressure engine, a distributing valve including a valve body provided with inlet and supply passages located on one side of an axial plane, and a valve ring surrounding said body and provided with a back pressure exhaust passage 130

in said ring and spaced from said inlet and supply passages.

12. In a valve for a fluid pressure engine, a distributing valve having an axially disposed inlet passage, supply passages radially disposed about said body, and a back pressure exhaust passage disposed in a semi-circular arc about the periphery of said body and diametrically opposite said supply passages.

13. In a valve for a fluid pressure engine, a distributing valve including a valve body comprising a hollow cylindrical portion forming an axially disposed inlet passage and a sectoral portion forming radially disposed supply passages, and a valve body ring comprising a circular, peripherally grooved portion forming a back pressure exhaust passage diametrically opposite said supply passages.

14. In a valve for a fluid pressure engine, a distributing valve including a valve body comprising a hollow cylindrical portion which forms an axially disposed inlet passage and a sectoral passage which forms radially disposed supply passages, and a circular valve body ring enclosing said body and slotted in part to permit projection of said sectoral portion therethrough and peripherally grooved opposite its slotted part to provide a back pressure exhaust passage.

15. In a valve for a fluid pressure engine, a distributing valve comprising a hollow, cylindrical portion of relatively small radius forming an axially disposed inlet passage and a sectoral portion of relatively large radius forming radially disposed supply passages, and a cut off plate positioned interiorly of said cylindrical portion.

16. In a valve for a fluid pressure engine, a distributing valve comprising a hollow, cylindrical portion of relatively small radius forming an axially disposed inlet passage and a sectoral portion of relatively large radius forming radially disposed supply passages, and a cut off plate positioned interiorly of said cylindrical portion, and an operating rod for said cut off plate positioned axially of said inlet passage.

17. In a valve for a fluid pressure engine, a distributing valve comprising a valve body and a valve body ring enclosing said body and split transversely with one end secured to said body, a bell crank fulcrumed on said

body with one of its arms engaging the unsecured end of said ring and the other of its arms movable radially of the valve by the internal pressure in said ring to contract said ring.

18. In a valve for a fluid pressure engine, a distributing valve including a ring, slotted peripherally throughout a portion of its length and split transversely, and a body including a sector shaped portion extending through the slotted portion of said ring, a pin securing one end of said ring to said body portion, a cylinder in said ring, a piston slideable in said cylinder and exposed to the interior and exterior pressure on said ring, a bell crank fulcrumed to said body portion with one arm engaging the other end of said ring and the other arm pivoted to said piston.

19. In a valve for a fluid pressure engine, a rotatable casing, a stationary valve body within the casing and provided with radial fluid pressure distributing passages having their open outer ends closed by the casing, said casing having ports for successive alignment with the outer open ends of the distributing passages.

20. In a valve for a fluid pressure engine, a casing, a valve body within the casing and having an axial inlet and radially disposed fluid pressure distributing passages leading from the axial inlet to the outer periphery of the valve body, the outer ends of the distributing passages being closed by the casing, the casing and the valve body being relatively rotatable with the casing having ports for successive alignment through the outer open ends of the distributing passages of the valve body.

21. In a valve for a fluid pressure engine, a casing having a circular interior, a circular valve body within the casing and provided with an axial inlet and radial passages leading from the inlet through the outer periphery of the valve body and closed by the casing, the casing having a series of ports, the casing and the valve body being relatively rotatable to bring the ports into successive alignment with the outer open ends of the distributing passages, the valve also having a back pressure exhaust channel in its outer periphery, said channel being of a length to communicate with opposite ports of the casing.

WILLIAM E. BAKER.
